SPINNING LINE SWIVEL

Louis H. Kennon, Houston, Tex.

Application January 15, 1938, Serial No. 185,246

3 Claims. (Cl. 255—1)

This invention relates to a spinning line swivel.

An object of the invention is to provide means specially adapted to be connected into a spinning line, or cable, to be used for screwing up sections of casing or pipe in the process of connecting them into a string as the same is lowered into a well and whereby the cable will be prevented from becoming twisted or kinked while the same is being manipulated in carrying on the work.

It is another object of the invention to provide a swivel adapted to be connected into the cable and adapted for connection to a tong which is arranged to be applied to the section of casing and whereby the section being connected into the string may be given the final turning movement to screw the same up tightly in the string.

In making up a string of casing or pipe as it is lowered into the well the sections are attached to the upper end of the string one at a time and in order to screw up the sections a cable is wound around the section being attached and one end of it is manipulated by a workman. The cable is also wound about the cat head of the draw works and the other end of the cable is manipulated by the driller. By suitably manipulating the cat head, with the cable drawn taut, both around it and around the casing section, the latter may be turned or spun so as to quickly screw it on to the string in the well. In order to tighten up the section being attached, that is, in order to screw it tightly on to the string beneath a tong is employed and a jerk line is attached to the tong handle and also to the cable and upon releasing the cable that is wound around the casing section and tightening up the cable on the cat head a sudden pull or jerk may be imparted, through the jerk line, to the tong to finally complete the work.

In order to prevent the cable from becoming twisted or kinked the swivel is connected into the operating cable, and the jerk line is also connected to the swivel and the cable may be readily manipulated, in a manner hereinafter explained, so that the casing section may be rotated, or turned alternately either through the operating cable itself or by means of the jerk line and tong to accomplish the purpose intended.

50 A novel method is thus employed in making up the casing or other well pipe.

With the above and other objects in view the invention has particular relation to certain novel features of construction, operation, and arrangement of parts, as well as to a novel method,

an example of which is given in this specification and illustrated in the accompanying drawings, wherein:

Figure 1 shows a horizontal sectional view of a derrick showing the floor, the rotary drilling machine and the draw works mounted thereon with the cable applied for spinning, or screwing up, the section of casing.

Figure 2 shows a similar view illustrating the cable as applied in manipulating the tong.

Figure 3 shows a plan view of the swivel employed.

Figure 4 shows a longitudinal, sectional view thereof, and

Figure 5 shows a fragmentary side view.

Referring now more particularly to the drawings wherein like numerals of reference designate the same parts in each of the figures, the numeral 1 designates a swivel housing to which the cap 2 is screwed. The cap has a central bearing 3 to receive the pin 4. The inner end of the pin has the nut 5 screwed thereon and between the nut and the outer end of the cap are the raceway rings 6, 7 between which are the antifriction bearings 8. On the outer end of the pin 4 there is the eye 9 to which one end of the operating cable 10 is attached. This cable, in operation, is wound around the cat head 11 of the draw works 12 and the free end of the cable may be manipulated by an operator so as to cause the cable windings about the cat head to frictionally engage or to release the cat head. The end of the housing 1 is provided with a tongue 13 which fits into a slot 14 of the swivel housing 15 and a pin 16 forms a pivotal connection between said housings 1 and 15. Screwed on to the outer end of the housing 15 is a cap 17 having a central bearing to receive the pin 18. Screwed on to the inner end of the pin 18 is a nut 19 and between this nut and the outer end of the cap 17 are the raceway rings 20 and 21 between which are the antifriction bearings 22. On the outer end of the pin 18 is the eye 23 and a section of the cable 10 has one end attached to the eye 23 and its other end is adapted to be wound about the section 24 of the casing to be screwed on to the string supported in the well from the rotary table 25. The other or free end of the cable which is wound around said casing section may be drawn taut so as to cause the portion of the cable coiled around the casing section to frictionally grip and turn the same when the cat head is operated and the driller holds the cable taut about the cat head. A straight line pull will thus be exerted through the

swivel, that is, the eyes 8, 23 will be in straight alignment with the cable which is operating to rotate the casing section.

On one side of the swivel housing 15 there is 5 an eye 26 for the attachment of one end of the jerk line 27 thereto. The other end of the jerk line is attached to the handle of the tong 28. This tong is swung in the derrick ready for application to the casing section as shown in Figure 1 but when the casing section is being rotated or screwed up as shown in Figure 1 the jerk line 10 is allowed to hang slack so as to allow the swivel to line up with the cable operating around the casing section 24. When the section is 15 screwed on to the string and it is desired to further tighten up the screw connection the tension of the cable around the section 24 is released and thereupon when the cat head 11 is rotated with the cable 10 drawn tautly around it 20 the swivel will swing over into the position shown in Figure 2 drawing the eyes 8 and 26 into straight alignment so that the jerk line 27 will come into alignment with the operative portion of the cable 10 whereby a straight line pull 25 may be exerted through said cable and jerk line. Meanwhile the tong 28 will be applied to the casing section 24, as shown in Figure 2 and said section may be tightly screwed up by a final pull on the tong handle.

30 During the manipulations above described the swivels will be permitted to turn as required to prevent twisting or kinking of the cable.

The drawings and description disclose what is now considered to be a preferred form of the 35 invention by way of illustration only, while the broad principle of the invention will be defined by the appended claims.

What I claim is:

1. A spinning line swivel comprising two cylindrical swivel housings, each having a bore in 40 one end provided with pin bearings, one housing having a groove in the other end, a tongue on the other end of the other housing which is

adapted to fit into the groove, means for pivotally connecting said tongue in the groove, eyes having pins, said pins and bearings being positioned in the bores of the swivel housings, means for maintaining the pins and bearings in the bores, an eye immovably connected to one of said 5 swivel housings and adapted to be aligned with the other housing by relative rotation of the tongue in the groove.

2. A spinning line swivel comprising two separate assemblies; each assembly being composed of a housing having an end bore, pin bearings in the bore, a pin retained in said bearings, means for retaining the pin and bearings in the bore; one of said assemblies having a groove, a 10 tongue on the other assembly working in the groove, means for pivotally connecting the tongue in the groove; an eye on the end of each assembly remote from the pivotal connection and which swivels about the axis of the respective 15 housing and another eye on the swivel adapted to be brought into and out of alignment with one of said housings upon relative rotation of the tongue on its pivot.

3. A spinning line swivel comprising two separate assemblies; each assembly being composed of a housing having an end bore, bearing means in the bore, a pin retained in said bearing means, a retainer for retaining the bearing means and pin in the bore; one of said assemblies having a 20 groove, a tongue on the other assembly working in the groove, a cross-pin for connecting the interfitting parts to allow rotation of the tongue in the groove; an eye on the end of each assembly 25 remote from said pivotal connection and which swivels, with the part on which it is mounted about the axis of the corresponding housing and another eye immovably connected to one of 30 said swivel housings and adapted to be aligned with the other housing by relative rotation of 35 the tongue in the groove.

LOUIS H. KENNON.
